UNITED STATES PATENT OFFICE.

JAMES SPILLANE, OF NEW YORK, N. Y.

CIGARETTE-CASE.

1,187,195.

Specification of Letters Patent. Patented June 13, 1916.

Application filed June 26, 1915. Serial No. 36,486.

To all whom it may concern:

Be it known that I, JAMES SPILLANE, a citizen of the United States, and a resident of the city of New York, Westchester, in the county of Bronx and State of New York, have invented a new and Improved Cigarette-Case, of which the following is a full, clear, and exact description.

The object of the invention is to provide a new and improved cigarette case arranged to permit of conveniently filling it with cigarettes, to allow of singly pushing the cigarettes partly out of the case for final removal by the user and to prevent injury to the cigarettes in the case especially while ejecting the same.

In order to accomplish the desired result, use is made of a box adapted to contain a row of cigarettes and having a delivery opening in one side near one end of the box, the latter having a slot in the said end, a spring-actuated follower in the said box adapted to exert a pressure on the cigarettes to hold the foremost cigarette in register with the said delivery opening, an ejector chamber in the said end of the box and having a slot leading into the box, an ejector slideable in the said chamber and provided with a finger piece extending through the said end slot to the outside of the box, the said ejector having one end passing through the said chamber slot and the said end having a foot piece adapted to engage one end of the foremost cigarette, the other end of which is in register with the said delivery opening, and a spring in the said ejector chamber and pressing the said ejector to normally hold the latter in retracted position. Use is also made of a covering plate extending over a portion of the box and provided with a guideway for a finger piece held on the spring-actuated follower to allow of conveniently retracting the follower when filling the box with cigarettes.

A practical embodiment of the invention is represented in the accompanying drawings forming a part of this specification, in which similar characters of reference indicate corresponding parts in all the views.

Figure 1 is a face view of the cigarette case with the foremost cigarette partly pushed out of the case for removal by the user; Fig. 2 is a similar view of the cigarette case with the cover opened and the ejector chamber shown in section; Fig. 3 is an edge view of the same with the cover in closed position; Fig. 4 is a transverse section of the same on the line 4-4 of Fig. 2; Fig. 5 is an enlarged sectional plan view of the same on the line 5-5 of Fig. 2; Fig. 6 is a perspective view of the ejector; and Fig. 7 is a similar view of the follower.

A box A of sheet metal or other suitable material is adapted to contain a row of cigarettes B and on one side of the said box A is hinged a cover C for normally keeping the box A closed. In the upper end of the box A is formed an ejector chamber D from which leads a slot E formed in the said upper end of the box A. In the right-hand side of the box A adjacent the right-hand side of the ejector chamber D is formed a delivery opening F for the passage of the foremost cigarette in the box A, as herein-after more fully explained, it being understood that the cover C is provided at its free side with a cut-out portion C' in register with the delivery opening F, (see Fig. 3) so as not to obstruct the free passage of the foremost cigarette. The inner or bottom wall D' of the chamber D is slightly concave to correspond to the concavity of the foremost cigarette B, as plainly shown in Fig. 4, and the edge of the wall D' adjacent the bottom of the box A is spaced from the latter so as to form a slot D². The foremost cigarette is adapted to be pushed partly out through the delivery opening F by the use of a foot piece G' of an ejector G arranged within the ejector chamber D. The ejector G is in the form of a blade having its inner end terminating in the foot piece G' provided with a guideway G² engaging the lower edge of the inner wall D' of the chamber D so as to guide the ejector G in its movement within the chamber D. A spring H is attached at one end to an upturned lug G³ formed on the right-hand side of the ejector G, the other end of the spring H being attached to the left-hand end of the chamber D. Thus by the arrangement described the ejector G is normally held in retracted position so that the foot piece G' engages the left-hand end of the foremost cigarette B, as plainly indicated in Fig. 2. The ejector G is provided with a finger piece

2

G⁴ extending through the slot E to the outside of the box A so that the user of the cigarette case can conveniently engage the finger piece G⁴ with a view to slide the ejector G 5 from the left to the right thus pushing the foremost cigarette partly through the delivery opening F to permit the user to finally pull the cigarette out of the box either by the use of one hand or the lips, as suits the 10 convenience of the user. The movement of the ejector G to the right is limited by the finger piece G⁴ reaching the right-hand end of the slot E. It is understood that when the cigarette has been pushed partly out 15 through the delivery opening F, the operator releases the finger piece G⁴ to allow the spring H to retract the ejector G so that when the foremost cigarette is finally withdrawn from the box A the foot piece G' is in 20 position for engaging the left-hand end of the next following cigarette.

The rearmost cigarette is pressed on by a follower I, pressed on by a spring J resting on the end of the box A opposite the one 25 containing the chamber D. The follower I is provided with a finger piece I' engaging a guideway K' in the form of a slot formed in a covering plate K fixed to the box A at the open face thereof so as to extend over 30 the cigarettes B to hold the same in place and to guide the movement of the spring-pressed follower I. The covering plate K terminates a distance from the ejector chamber D at the delivery opening F to provide 35 a filling space for conveniently placing the cigarettes in position in the box A when filling the same into the box. It is understood that when placing the cigarettes in the box, the user takes hold of the 40 finger piece I' and pushes the same downward to move the follower I in a like direction and against the tension of its spring J. The covering plate K is provided with a wide slot K² parallel to the 45 guideway K' and extending from the free end of the covering plate K a distance toward the other end of the said covering plate. The slot K² is sufficiently wide for the insertion of a finger to enable the user 50 to conveniently place the cigarettes in proper position one on top of the other when filling the box A with cigarettes. It is understood that the cigarettes are usually oval in cross section, and in order to permit of placing as 55 many cigarettes as possible into the box the cigarettes are super-imposed in the direction of their minor axes, as will be readily understood by reference to Fig. 4.

In filling the box A with cigarettes, the 60 cover C is swung open, and after the box is filled the cover C is closed. When it is desired to remove a cigarette from the box it is only necessary for the user to exert a push on the finger piece G⁴ so as to move the same

along in the slot E and thus cause the foot 65 piece G' of the ejector G to push the foremost cigarette partly out of the delivery opening F, as previously explained. The user then releases the pressure on the finger piece G⁴ to allow the ejector to return to normal inactive position, and then the foremost cigarette is pulled completely out of the box A. When this takes place, the spring-pressed follower I pushes the remaining cigarettes forward in the box A until 70 the foremost cigarette is in contact with the wall D' and its left-hand end is engaged by the foot piece G'.

The cigarette case shown and described is very simple in construction and the cigarettes can be singly ejected whenever it is desired to do so, and the cigarettes are not liable to be injured while filling the same into the box A or while sliding the same in the said box under the protecting covering 85 plate K.

Having thus described my invention, I claim as new and desire to secure by Letters Patent:

1. In a cigarette case, the combination of 90 a box adapted to contain a row of cigarettes and having a delivery opening in one side near one end of the box, the latter having a slot in the said end, a spring-actuated follower in the said box adapted to exert a 95 pressure on the cigarettes to hold the foremost cigarette in register with the said delivery opening, an ejector chamber in the said end and having one edge of its bottom wall spaced from the box to provide a slot 100 leading into the box, an ejector slidably in the said chamber and provided with a finger piece extending through the said end slot to the outside of the box, the said ejector having one end extending through the said 10 chamber slot, and having on the said end a foot piece adapted to engage one end of the foremost cigarette the other end of which is in register with the said delivery opening, the said foot-piece having a guide-way engaging the edge of the said bottom wall of the ejector chamber, and a spring in the said 11 ejector chamber and pressing the said ejector to normally hold the latter in retracted position.

2. In a cigarette case, the combination of 12 a box adapted to contain a row of cigarettes and having a delivery opening in one side near one end of the box, a fixed covering plate on the said box and terminating a distance from the said end of the box, the said covering plate having a guide-way, a spring actuated follower in the said box and adapted to exert a pressure on the cigarettes to hold the foremost cigarette in register with the said exit opening, and a finger piece on the said follower and slidably engaging the 13 said guideway in the covering plate, the lat-

ter having a slot extending parallel to the guideway from the free end of the covering plate to within a distance of the other end of the plate to allow of inserting a finger 5 for manipulating the cigarettes on filling the box with cigarettes.

In testimony whereof I have signed my

name to this specification in the presence of two subscribing witnesses.

JAMES SPILLANE.
